UNITED STATES PATENT OFFICE

ANDRÉ VIGNEAU, OF PARIS, FRANCE, ASSIGNOR TO SOCIETE DES ANCIENS ETABLISSEMENTS SIEGEL & STOCKMAN REUNIS, OF SEINE, FRANCE

DESIGN FOR A LAY FIGURE FOR DISPLAY OF GARMENTS

Application filed December 27, 1929, Serial No. 33,964, and in France August 3, 1929. Term of patent 7 years.

To all whom it may concern:

Be it known that I, ANDRÉ VIGNEAU, a citizen of the French Republic, residing at 5, Cité Cardinal Lemoine, Paris, Seine, France, have invented a new, original, and ornamental Design for Lay Figure for Display of Garments, of which the following is a specification, reference being had to the accompanying drawing, forming part thereof.

I claim:

The ornamental design for a lay figure for display of garments, as shown.

ANDRÉ VIGNEAU.
